UNITED STATES PATENT OFFICE.

WILLIAM M. COOPER AND JOHN WESLEY CATES, OF LA SALLE, TEXAS.

DESIGN FOR A HORSESHOE.

SPECIFICATION forming part of Design No. 27,644, dated September 14, 1897.

Application filed July 8, 1897. Serial No. 643,911. Term of patent 14 years.

To all whom it may concern:

Be it known that we, WILLIAM M. COOPER and JOHN WESLEY CATES, citizens of the United States, residing at La Salle, in the county of Limestone and State of Texas, have invented and produced a certain new and original Design for Horseshoes; and we do declare the following to be a full, clear, and exact description of the invention, such as will enable others skilled in the art to which it applies to make and use the same.

Our invention relates to a new and original design for horseshoes, and the leading feature of the design comprises the flat lips 2, 15 projecting upwardly from the outer edge of

the shoe and inwardly toward the center and formed with parallel sides *a* to *b* and tapering sides from *b* to *c* and with holes *d*.

What we claim is—

The design for a horseshoe as herein shown 20 and described.

In testimony whereof we hereunto affix our signatures in presence of two witnesses.

WILLIAM M. ^{his} X COOPER.
JOHN WESLEY CATES. ^{mark}

Witnesses:

J. W. HESSING,
C. S. BOND.
